CAN CLOSURE

Clarence D. Harris and Tressel R. David,
Nampa, Idaho

Application April 16, 1934, Serial No. 720,852

3 Claims. (Cl. 220—55)

This invention relates to a securing means for a milk can lid, and has for its object the production of a simple and efficient securing or holding means for a milk can lid which will automatically snap into a locking position and which may be also easily released by exerting pressure upon the lid and lifting the same.

Another object of the invention is the production of a simple and efficient latch mechanism carried by a milk can lid, the latch mechanism being so constructed as to automatically snap into a locking position when the lid is forced to a closed position upon the neck of a milk can, and at the same time may be released by exerting outward pressure on the lid.

A further object of this invention is the production of a simple and efficient locking device for a can lid which will automatically spring to a locking position for preventing the accidental removal of the lid from the can.

Other objects and advantages of the present invention will be apparent throughout the following specification and claims.

In the drawings:—

Figure 1 is a vertical sectional view through a portion of a can showing the lid in its closed or locked position;

Figure 2 is a vertical sectional view through the can and lid taken at right angles to Figure 1;

Figure 3 is a horizontal sectional view taken on line 3—3 of Figure 2;

Figure 4 is a sectional perspective view of a portion of the can and lid illustrating in detail the latching device;

Figure 5 is a vertical sectional view through a modified form of can and lid holding or locking structure;

Figure 6 is a section taken on line 6—6 of Figure 5; looking in the direction of the arrow;

Figure 7 is a section taken on line 7—7 of Figure 6;

Figure 8 is a vertical sectional view of a modified form of can and cover of the present invention;

Figure 9 is a section taken on line 9—9 of Figure 8; and

Figure 10 is a detail perspective of the latching member used in connection with the form of device illustrated in Figures 8 and 9.

By referring to the drawings, it will be seen that 10 designates a can of the conventional type having an inclined shoulder portion 11 terminating in a vertically extending restricted neck 12.

A lid 13 of the conventional type is used in conjunction with the can 10 and comprises an in-

wardly extending collar portion 14 which is adapted to fit within the restricted neck 12 of the can. This collar portion 14 carries upon each side thereof, a latching member 15, the latching members 15 being secured to the inner face of the collar portion 14 by means of suitable rivets 16. The latching members 15 are bowed outwardly with respect to the collar 14, as indicated at 17, to provide a suitable spring action, and these latching members 15 are preferably formed of spring material and the lower ends of the latching members 15 normally lie snugly against the lower edge 18 of the collar 14. A slightly bowed transversely extending locking bar 19 is secured to the lower end of each latching member 15 and this bowed locking bar 19 is preferably substantially circular in cross-section as indicated at 20, with the exception that the rear face is flattened as at 21, in order to permit the locking bar 19 to be securely soldered or otherwise fastened to the inner flattened face of the spring latching member 15, as shown in Figure 4. This locking bar 19 is preferably of an elongated structure so as to extend laterally of the latching member 15 for a considerable distance and 25 provide a wide gripping surface.

In the form shown in Figures 1 to 4 inclusive, it will be noted that the locking bar 21 is adapted to fit under the upper edge of the inclined shoulder portion 11, and thereby firmly hold 30 the lid against accidental displacement from the can. The rounded face of the locking bar 21, however, will permit the cover to be released from the can when pressure is exerted outwardly upon the lid, but under normal conditions the latching 35 member 15 in conjunction with the locking bar 21 will firmly hold the lid against accidental displacement.

In Figures 5, 6, and 7, there is shown a modified form of the invention wherein the lid 13 carries the usual latching members 15 and the locking bar 19 previously described, the only difference in the two forms being in the construction of the can which is indicated by the numeral 22. This can 22 is provided with an 40 upstanding restricted neck 23 in which neck 23 is formed an annular bead 24 near its lower end and above the inclined shoulder 25. This bead 24 is adapted to receive the locking bar 19 previously described, when the lid 13 is secured to 45 a can, such as illustrated by the numeral 22, and the locking bar 19 by fitting snugly within the beaded channel 24 will efficiently hold the lid against accidental displacement and at the same 50 time permit the lid to be easily snapped into and 55

out of position. It should be understood that the latching member 15 and locking bar 19 are identical, the only difference being in the construction of the can itself.

5 It should be noted that certain detail changes in the mechanical construction may be employed without departing from the spirit of the invention, so long as such changes fall within the scope of the appended claims.

10 By referring particularly to Figure 8, it will be seen that 26 designates the can which is provided with an inclined shoulder portion 27 terminating in an upstanding neck 28, the neck 28 having an outturned lip 29 at its outer extremity, 15 the lip 29 terminating in a beaded portion 30.

A lid 31 having an annular neck portion 32 is adapted to fit within the upstanding neck 28 of the can 26, which lid 31 has the edge thereof provided with a downwardly extending protector flange 33 around its marginal edge for snugly fitting over and shielding the outturned flange 29 of the neck 28. The outturned flange 29 will facilitate the guiding of the neck 32 into the neck 28. The annular neck portion 32 is provided with an annular bead 34 near its inner end which is adapted to rest upon the outturned flange 29 of the neck 28 and limit the inward movement of the neck portion 32 within the neck 28. The neck portion 32 is provided with elongated slots or cut-out portions 35 near the lower edge of the annular neck 32, as shown in Figures 8 and 9.

35 A spring latching member 36 is secured to each side of the neck portion 32 upon the inner face of the neck as shown in Figure 8 and each of these latch members 36 is provided with an outwardly bowed spring portion 37 which terminates in a transversely extending locking bar 38 which is preferably rounded upon its inner face and having its ends projecting beyond the sides of the bowed portion 37, as shown in Figures 9 and 10. The locking bars 38 of the latching members 36 are adapted to project through the slots 35 and contact with the under 40 face of the shoulder portion 27 at a point near the junction of the neck 28 with the shoulder 27, the spring or bowed portion 37 of the latching member 36 tending to hold this locking member 38 in contact with the under face of the shoulder 27, as shown in Figure 8. The locking members 38 are preferably elongated to provide a wide or long gripping face upon the can.

Having described the invention, what is claimed as new is:—

1. In combination, a can having a neck substantially circular in cross section, the neck having a circumferentially extending abutment portion, a cover having a depending collar of a diameter to fit snugly within the can neck, and spring latching members carried by said collar to releasably hold the cover upon the can neck, each latch consisting of a strip of resilient material extending longitudinally of the collar and secured at its upper end to the collar, the lower end of the strip being free, and a cross bar of rigid material carried by the lower end portion of the strip and secured intermediate its length to the strip with its end portions projecting from opposite sides of the strip, the cross bar being curved longitudinally and providing an elongated gripping member adapted to engage the abutment of the can neck for an appreciable distance circumferentially of the neck whereby the cover will be firmly but detachably held in place.

2. In combination, a can having a neck provided with a circumferentially extending abutment portion, a cover having a collar to fit snugly within the neck and having cut-outs formed in spaced relation to its lower end exposing portions of the abutment portion of the neck when the cover is in place, and latches consisting of 30 spring strips extending longitudinally of the collar and secured at their upper ends to the collar, and cross bars carried by lower end portions of the spring strips and providing elongated grippers extending through the cut-outs for engaging the abutment portion of the neck to securely but releasably hold the cover to the neck.

3. In combination, a can having a neck provided with a circumferentially extending abutment portion, a cover having a collar to fit snugly 40 within the neck, and latches consisting of spring strips extending longitudinally of the collar and secured at their upper ends to the collar, and cross bars carried by the lower end portions of the spring strips and providing elongated grippers for engaging the abutment portion of the neck to securely but releasably hold the cover to the neck.

CLARENCE D. HARRIS. 50
TRESSEL R. DAVID.
